UNITED STATES PATENT OFFICE.

AB HOLLAND, OF FORREST CITY, ARKANSAS, ASSIGNEE OF ONE-HALF TO SYDENHAM
B. TRAPP, JR., OF FORREST CITY, ARKANSAS.

CULTIVATOR.

1,105,198.

Specification of Letters Patent. Patented July 28, 1914.

Application filed May 20, 1913. Serial No. 768,802.

To all whom it may concern:

Be it known that I, AB HOLLAND, a citizen of the United States, residing at Forrest City, in the county of St. Francis and State of Arkansas, have invented certain new and useful Improvements in Cultivators, of which the following is a specification, reference being had therein to the accompanying drawing.

10 This invention relates to certain new and useful improvements in cultivators and more particularly to that class of cultivators known as "straddle row cultivators"; the object being to provide a cultivator which is 15 so constructed that two rows can be cultivated at the same time.

Another object of the invention is to provide novel means for adjusting the teeth-carrying bars, whereby they can be thrown 20 at any angle desired in order to conform to the inclination of the hill or row being cultivated.

Another object of the invention is to provide a cultivator in which each cultivating 25 member is adjustable laterally in respect to the body of the cultivator in order to allow the same to be adjusted according to the width of row being cultivated.

Another object of the invention is to provide a cultivator which is exceedingly simple 30 and cheap in construction, and one in which the parts are so arranged and mounted, that they can be adjusted from the driver's seat without dismounting from the cultivator.

35 Other and further objects and advantages of the invention will be hereinafter set forth and the novel features thereof defined by the appended claims.

In the drawings—Figure 1, indicates a 40 front elevation of my improved cultivator; the tongue being shown in section; Fig. 2, is a top plan view of the cultivator; the tongue being broken away; Fig. 3, is a rear elevation of the cultivator; Fig. 4, is a detail longitudinal section; Fig. 5, is a detail transverse section showing the manner of 45 pivotally mounting the teeth-carrying bars; and Fig. 6, is a detail transverse section through the body, showing the manner of 50 mounting the laterally adjustable members.

Like numerals of reference, refer to like parts in the several figures of the drawings.

In the drawings, 1 indicates the body of 55 the cultivator which is provided with a tongue 2 carrying a draft-bar 3 to which

the swing trees are adapted to be connected in the ordinary manner. The body is provided with a transverse bore 4 forming a guide-way in which the tenon portions 5 and 6 of bars 7 and 8 are mounted and can 60 be locked in a rigid position by screws 9 as clearly shown, but in ordinary use, these screws are moved out of engagement with the tenons in order to allow the same to be adjusted laterally. The draft-bar is connected at its outer ends to the bars 7 and 8 by chains 10, as clearly shown, and the body 1 is provided with a seat 11.

Secured to the rear portion of the body in suitable keepers 12, are operating bars 13 mounted in guide-ways 14 secured upon the rear of the bars 7 and 8. Connected to these bars to each side of the driver's seat is an operating lever 15; the lower end of which is pivotally connected to the respective bar and each lever has a pivotal and slidable connection with the bar 13, as shown at 16 so that by drawing the operating levers toward the driver's seat, the bars can be moved away from the body so as to adjust the cultivator to the width of the row being cultivated and after having been adjusted, the screws 9 can be tightened and the same will be locked in its adjusted position. It will be seen that the means for adjusting the bars 7 and 8 laterally are formed exactly 75 alike, and the description of one will be sufficient for both.

Each of the bars 7 and 8 are formed exactly alike and are provided with grooves in their under faces in which are pivotally mounted teeth-carrying bars 17 and 18 provided with teeth 19; said bars being mounted upon pivot pins 20 as clearly shown, in order to allow the same to swing freely and it will be seen that by mounting the upper ends of the bars within the grooves, they will be prevented from yielding rearwardly by the pressure exerted when brought into contact with the side of the hill.

Connected to each of the teeth-carrying bars 17 and 18, is a rod 21 which extends up through an opening formed in the bar adjacent its end, and said rods are connected to an operating bar 22 arranged upon the 105 top of the bars 7 and 8 as the case may be. Extending upwardly from the sides of the bars 7 and 8 are standards 23 provided with spaced openings through which a pin 24 is adapted to be forced in order to limit the 110

upward movement of the bar so as to regulate the expansion of the toothed bar by the weight of the operator upon the body and it will be seen that by this construction, the 5 toothed bars can be adjusted at any inclination desired and maintained in that position.

In order to prevent the bars 7 and 8 from being twisted from the body when brought into contact with the ground, each bar is 10 connected to the tongue 2 by a rod 25; the forward end of said rod being adjustably mounted within an apertured plate 26 carried by the tongue so that when the bars 7 and 8 are forced laterally by removing 15 the rods 25 from the plate 26, the bars will be free to move and after having been adjusted by forcing the rod into one of the openings of the plate 26, they will be held in that position. In order 20 to provide means for operating the rod 25, a standard 27 is formed on the tongue 2 carrying pivotally and slidably mounted operating levers 28; the lower ends of which carry rods 29 which are slidably mounted 25 upon the rods 25 in order to allow the rods to be detached from the plate 26 by the operator without dismounting from the cultivator.

I claim:

30 1. A cultivator, comprising a body having a pair of tooth bars pivotally mounted upon horizontal pivots and capable of swinging toward and away from each other, a vertical rod carried by each of said tooth bars, an operating bar connecting said rods and mounted upon said body, and means carried by said body for preventing upward movement of said operating bar.

2. A cultivator, comprising a body having 40 a pair of tooth bars pivotally mounted upon horizontal pivots and capable of swinging toward and away from each other, a rod carried by the free end of each of said tooth bars and extending through said 45 body, an operating bar mounted upon said body having a connection with each of said rods, spaced apertured standards extending upwardly from said body, and a pin passing through the apertures of said 50 standard for preventing upward movement of said operating bars.

3. A cultivator having a body carrying a bar, said bar having a grooved under face, tooth bars pivotally mounted in the 55 groove of said bar, rods connected to said tooth bars extending through apertures formed in said bar, an operating bar mounted upon said body and connected to said rods, spaced standards carried by said

bar, and a pin connecting said standards 60 for preventing upward movement of said operating bar.

4. A cultivator comprising a body carrying a bar having a grooved under face, diverging tooth bars pivotally mounted in 65 said groove, rods carried by said tooth bars extending through the apertures formed in said bars, an operating bar connected to said rods, apertured standards carried by said bar, and a pin adjustably mounted in 70 said apertured standards for limiting the upward movement of said operating bar.

5. A cultivator having laterally adjustably mounted tooth bar carrying members, vertically arranged tooth bars carried by 75 said members capable of swinging toward and away from each other, and an adjustable connection between said tooth bar carrying members and said cultivator.

6. A cultivator comprising a body having 80 a tongue, bars adjustably mounted in said body, rods carried by said bars adjustably connected to said tongue, a standard carried by said tongue, and levers mounted upon said standard having a sliding connection with said rods.

7. A cultivator comprising a body having 85 a tongue carrying a draft bar, said body being provided with a guide-way, bars slidably mounted in said guide-way, means for operating said bar, means for locking said bars in an adjusted position, a connection between said bars and draft bar, a connection between said bars and tongue, and adjustably mounted tooth bars carried 95 by said bars.

8. A cultivator comprising a body carrying 90 adjustably mounted bars, tooth bars pivotally mounted in said bars, rods carried by said tooth bars extending through 10 said bars, an operating lever connected to said rods, and means for holding said operating lever in its adjusted position.

9. A cultivator, comprising a body provided with laterally extending bars having 10 grooved under faces, spaced tooth bars pivotally mounted in said grooves and depending therefrom, means for adjusting said bars toward and away from each other in order to increase or decrease the inclination thereof, and means for holding said bars in adjusted position.

In testimony whereof I affix my signature in presence of two witnesses.

AB HOLLAND.
